PRESS FOR CUTTING METAL AND OTHER SHEETS

Harry Albert Griffiths, Edgbaston, Birmingham,
EnglandApplication October 27, 1934, Serial No. 750,377
In Great Britain September 8, 1933

11 Claims. (Cl. 164—87)

This invention has for its object to provide an improved press for use in the cutting of circular or other blanks from metal or other sheets.

The invention comprises the combination with an inclined guide and a work holder slidable on the guide, of means for imparting intermittent upward movements to the slide along the guide, and means for effecting intermittent downward movements of the slide along the guide under the action of gravity.

Also the invention comprises the combination with the said inclined guide, of means for imparting to it intermittent lateral movements as hereinafter described.

In the three accompanying sheets of explanatory drawings:—

Figure 1 is a sectional side elevation and Figure 2 a plan illustrating a mechanism constructed in accordance with this invention.

Figure 3 is a front elevation showing the horizontal guide and associated parts, whilst Figure 4 is a side elevation of the inclined guide and associated parts.

In carrying the invention into effect in the manner illustrated, a fixed horizontal guide bar *a* is arranged on the main frame *b* of the machine at the front or one side of the cutting tools. These latter are not shown but they are of the usual form consisting of a punch and die, and their axis is arranged at an angle of about 30° to the vertical. On the guide *a* is arranged a slide *c* carrying an inclined bed *d*, the plane of movement of this bed being at right angles to the axis of the tools. On the inclined bed is mounted a guide bar *e* which carries a slide *f* serving as the sheet holder, the sheets to be cut being held by any convenient form of grippers indicated in Figure 2 by *g*. The slide *f* is moved upwardly on the inclined guide *e* by mechanical means to be hereinafter described, and the downward movement is effected by gravity. The slide *c* and bed *d* in addition to being carried on the guide bar *a* are also supported by fixed guide bars *h* with which engage rollers *i* mounted beneath the bed *d*.

On the slide *c* there is arranged a notched rack *j* which is engaged by a pivoted locking pawl *k* carried by a fixed bracket *l* on the bed of the machine. The pitch of the rack notches is equal to the spacing of the rows of blanks to be cut from the sheet, and the engagement of the pawl with any of the notches serves to hold the slide *c* and bed *d* on the guides *a* and *h* while a row of blanks is being cut from the sheet. After a

row of blanks has been cut and prior to the cutting of the next row, the slide is moved along the guides, and is then held by the re-engagement of the pawl with another notch.

The intermittent movements of the slide *c* on the horizontal guides *a* and *h* towards the tools after the completion of each row is effected by suitable means as hereinafter described. The return movement of the slide is effected by a weight *m* after disengagement of the locking pawl *k*. The weight also serves to hold one side of each rack notch in turn firmly in contact with the pawl *k* for accurately locating the sheet relatively to the tools.

On the guide *e* carried by the inclined bed *d* are arranged two fixed racks *n*, *o*, and a reciprocating rack *p*. Each of these is engaged by a pawl *q*, *r*, *s*, respectively on the slide *f*. Any convenient means such as are hereinafter described are employed for reciprocating the movable rack *p*. In its upward movements the rack *p* carries the slide *f* and sheet from one position to the next in the operation of cutting out a row of blanks. During the return movements of the rack *p* the slide is held by the pawl *q* engaging the fixed rack *n*, the pawl being held firmly against a notch in the rack by the action of gravity on the slide during the cutting operation. After the slide has reached the upper limit of its movement, the guide *c* with bed *d* are moved to the next position on the horizontal slides *a*, *h*, and the two pawls *r* and *q* engaging the reciprocating rack *p* and the fixed rack *n* respectively are put out of action. The inclined slide now returns step by step under the action of gravity to its lower limit of movement for the cutting out of the next row of blanks. This movement is controlled by the third pawl *s* which engages the other fixed rack *o*, the pawl being momentarily and successively raised out of engagement with any one of the notches in the rack and allowed immediately afterwards to engage the next notch. Further details of this device are described below.

After all the blanks have been cut out from the sheet, the horizontal slide *c* and bed *d* are moved by the weight *m* above-mentioned to their initial position in readiness for action on the next sheet. After the cutting operations the scrap portion of the sheet falls away by gravity or, is ejected at the back of the press.

Reverting to the means for actuating the slide *f*, this slide as already mentioned receives its intermittent movements up the bed *d* from the

reciprocating rack *p*. This rack as shown in Figures 1 and 2 is supported at its upper end by a bearing *t* on the bed *d*. At its lower end it is secured adjustably to a bar *u* slideable on bearings 5 at the underside of the bed *d*. This bar *u* is formed with a projection *v* which engages and can slide along a grooved channel *w* carried on a pair of slides *x* which are reciprocated continuously by cranks *y* through links *z*, the cranks 10 receiving their motion from any convenient part of the driving mechanism of the press and being coordinated with the movements of the tools. By the reciprocation of the rack *p* which is correlated with the action of the cutting tools, the 15 slide *f* together with the sheet to be acted on by the tools are carried upwards along the bed *d* with a step-by-step motion. In each interval of rest a blank is cut from the sheet, and return movement of the slide is prevented by the engagement of the pawl *q* with the fixed rack *n*. When the slide *f* reaches the upper end of its travel the pawls *q* and *r* are put out of action. This is effected by a lever 2 on one side of the 20 slide which can engage a tappet 3 on the bed *d*. While moving relatively to the tappet the lever is rocked and thereby caused to actuate through a link 4 a pair of cams 5 which lift the pawls against the action of springs 6. The slide *f* is now free, but return motion is prevented by the 25 engagement of the pawl *s* with the rack *o*. When it is desired to cut out the blanks in certain rows in staggered relation to the blanks in the preceding row the notches in the rack *o* are so arranged that after the pawls *r*, *q*, have been released the slide *f* is allowed to fall back immediately through a distance equal to one half of the pitch of the blank and is arrested at the end of this movement by the engagement of the pawl *s* with the first notch in the rack *o*. To effect 30 the intermittent return of the slide *f* along the bed *d* under the action of gravity, the pawl *s* is intermittently released. This is effected by a bar 7 (Figures 1, 2 and 4) carried at its ends by levers 8 to which is attached another bar 9. The latter is moved longitudinally by a lever 10, a lever 11 and a striking bar 12 attached to the front of the channel *w*. During the movement of the bar 12 in the direction of the arrow (Figure 4) the lever 11 moves the lever 10 and bar 9 in 35 the direction for lifting the bar 7 and so raising the pawl *s* away from the rack. The slide *f* can move by gravity along the bed *d* until it is arrested by re-engagement of the pawl *s* with the next notch in the rack. Meanwhile the lifting 40 bar 7 and its operating means have returned to their initial position, or they are returned by the pressure of the pawl *s* under the action of the spring 13 acting on the pawl. During the return motion of the bar 12 it again strikes the lever 11, 45 but this action is ineffective owing to the provision of a pin and slot or other lost motion connection between the levers 10 and 11. A blank is cut from the sheet during each interval of rest. 50

It will be understood that the mechanism associated with the rack *o* is working continuously owing to its permanent connection with the levers *y*, but the said mechanism is only effective during the descending movement of the slide *f* on the bed *d*, as during the upward movement the 55 slide is controlled by the pawls *q* and *r*.

When the slide *f* reaches its lower position, it is arrested by a stop 14, but immediately prior to reaching the stop the lever 2 is engaged by another tappet 15 causing the lever 2 to be rocked 60 in the opposite direction to that above described

and the pawls *q* and *r* to be again brought into action. The slide *f* now recommences its upward movement and at the same instant the bed *d* is given another movement on the guides *a*, *h*, and the above described cycle of operations is repeated. 5

As regards the means for moving the slide *c* and bed *d* on the guides *a*, *h*, this is shown in Figures 1, 2 and 3. Along one side of the slide *c* (of which only a small piece is shown in Figure 10 3 to avoid confusion with other parts required to be illustrated in that view), there is secured a rack *j* as already mentioned, and this is engaged by a locking pawl *k*. Parallel with the rack is mounted on the bed of the machine a 15 reciprocating bar 16 on which is pivoted a pawl 17 adapted to engage any one of a number of notches in the rack *j*. The bar 16 is continuously reciprocated by a bell crank 18 acting through a link 19, the crank 18 receiving its motion from 20 any convenient part of the driving mechanism of the press. Alongside and between the rack *j* and bar 16 is arranged a bar 20 the purpose of which is to control the pawl 17. The bar 20 as shown in Figure 3 is carried at its ends by levers 25 21 whereby longitudinal movement of the bar is accompanied by an upward and downward movement. The said bar 20 is reciprocated only when the slide *f* reaches either the top or the bottom of its travel, and the motion of the bar is derived 30 from a suitably timed cam or other means actuated by the driving mechanism of the press and coordinated with the travel of the slide *f*. As shown in Figure 3 the pawl 17 is out of action. When the bar 20 is moved to the right it allows 35 the pawl to drop into engagement with the rack *j* and movement is then given to the rack through the pawl when the bar 16 moves towards the left. The locking pawl *k* does not interfere with this movement as the notches in the rack 40 bar *j* are each formed at one side with an inclined edge. When the bar 16 is moving towards the right, the rack *j* is held by the pawl *k* and is pulled tightly against one side of that pawl by the weight *m*. At the same time the bar 20 returns towards the left and raises the pawl 17 45 out of action so that further movement cannot be given to the bed *d* until the slide *f* reaches the other limit of its travel.

When the bed *d* reaches the end of its travel 50 along the guides *a*, *h*, in the manner above described, and the scrap portion of the sheet has been removed, the bed is returned to its initial position prior to the insertion of another sheet. The return movement of the bed is effected by the weight *m* after the release of the locking pawl *k*. This release is effected in the following manner. The pawl *k* at the side opposite that which engages the rack is acted on by a bar 22 which is attached to the pawl (Figure 1). This bar is urged in the upward direction for engaging the pawl with the rack by a spring 23. The bar is moved in the opposite direction for releasing the pawl by a bell crank lever 24 (Figure 3) which is actuated momentarily by a rod 25 connected to a cam or other means driven by the mechanism of the press and suitably co-ordinated with the movement of the bed *d*. After the bar 22 has been moved in the downward direction it is held by a spring controlled catch 70 lever 26 pivoted on the bracket *l* and arranged to swing over the top of the bar. The latter cannot now move again until the bed under the action of the weight *m* has reached its initial position, or nearly so, when the tappet 27 on the 75

bed strikes the catch and withdraws it from engagement with the bar 22. This bar under the action of the spring 23 now returns the pawl *k* to its active position in readiness for repetition of the movements above described.

To minimize shock when the bed reaches its initial position, there is mounted on the bed a buffer piece 28 acted on by a strong spring 29 and arranged to engage an inclined surface 30 on the stop collar carried by the bar *a*. While the buffer is moving along that surface the spring is compressed and the momentum of the bed is thereby absorbed.

To enable the machine to be readily adapted for cutting out blanks of different sizes, involving different spacings of the rows in the sheet, all the racks are made readily removable so that suitable racks can easily be mounted in the machine, and the locking pawl *k* is mounted adjustably on the bed of the machine, the bracket *l* being movable on its support by a screw 32.

It sometimes is required to be able to lower the slide *f* along the bed *d* while the pawls *q*, *r*, are out of action, as for example when setting up the machine, and to enable this to be done there is combined with the pawl *s* a hand lever 33 acting through a link 34 on a cam 35. By movement of the hand lever the pawl can be lifted out of action and the slide is then free.

By this invention I am able to simplify greatly the design and construction of machines of the kind to which the invention relates, to accelerate the normal rate of working and also to obviate obstruction to free movement of the blanks and the scrap away from the machine.

Having thus described my invention what I claim as new and desire to secure by Letters Patent is:—

1. In presses for cutting metal and other sheets, the combination of a longitudinally inclined guide, a work holder slidable along the guide, a pair of fixed racks and a reciprocatory rack carried and arranged longitudinally on the guide, pawls on the work holder for engaging the racks, means associated with one of the fixed racks for intermittently raising out of action the pawl engaging that rack, and means for putting the other two pawls out of action throughout the downward travel of the work holder, the arrangement of the parts being such that engagement of the two latter pawls with their racks serves to effect and control the movement of the work holder in the upward direction on the guide, whilst the return motion is effected by gravity under the control of the other rack and pawl, substantially as described.

2. The combination with mechanism as claimed in claim 1, of means for raising out of action the two pawls which are operative during the upward movement of the work holder when the latter reaches the upper end of its travel and for re-engaging the pawls with the racks when the work holder reaches the lower end of its travel, substantially as described.

3. The combination with mechanism as claimed in claim 1, of springs associated with the pawls which are operative during the upward movement of the work holder, a lever and cam device for raising said pawls out of action against the springs, and tappets on the slide for automatically actuating the said device at each end of the travel of the work holder, substantially as described.

4. In mechanism as claimed in claim 1, operating means for the reciprocatory rack, comprising

ing an oscillatory lever, a slide actuated by the said lever, a channel member arranged transversely to the direction of motion of the said slide, and another slide arranged parallel with the first slide and actuated by engagement with the said channel member, the second slide being connected to the rack, substantially as described.

5

5. The combination with the mechanism claimed in claim 1, of a pawl controlling bar situated alongside the rack associated with the gravity movements of the work holder, a spring for holding the corresponding pawl in engagement with the last mentioned rack, and means for imparting longitudinal and rising and falling movements to the said bar, the bar by its rising movement being adapted to raise the pawl out of action against the force of said spring, substantially as described.

10

6. In mechanism as claimed in claim 1, the combination with the rack associated with the gravity movements of the work holder and the pawl engaging that rack, of a longitudinally arranged pawl controlling bar, levers carrying said bar, a lever device for imparting rising and falling as well as longitudinal movements to the said bar through the said levers, and a reciprocatory member for actuating the said lever device, the latter being such that movement of the reciprocatory member in one direction only is utilized to operate the device, substantially as described.

15

7. In mechanism as claimed in claim 1, the combination with the rack associated with the gravity movements of the work holder and the pawl engaging that rack, of a pawl controlling bar, levers carrying the bar adapted to impart thereto rising and falling as well as longitudinal movements, a lever device for actuating the bar through the said levers, a reciprocatory member for actuating the said lever device, the latter being such that movement of the reciprocatory member in one direction only is utilized to operate the device, and hand operated means for putting the pawl out of action, substantially as described.

30

8. In presses for cutting metal and other sheets, the combination with mechanism as claimed in claim 1, of means for imparting intermittent lateral movements to the inclined guide, substantially as described.

40

9. In mechanism as claimed in claim 1, the combination of a fixed horizontal guide, a rack mounted on the inclined guide, a locking pawl engaging the rack, a reciprocatory bar, an operating pawl carried by the bar and adapted to engage the rack, means for reciprocating the said bar, means for intermittently engaging and disengaging the operating pawl and the rack, and a weight acting on the inclined guide for holding it against the locking pawl and for returning the said guide to its initial position after the movements under the action of the operating pawl have been completed, substantially as described.

45

10. In mechanism as claimed in claim 1, the combination of a fixed horizontal guide, a rack mounted on the inclined guide, a locking pawl engaging the rack, a reciprocatory bar, an operating pawl carried by the bar and adapted to engage the rack, a bar for controlling the latter pawl, and means for imparting longitudinal and rising and falling movements to the controlling bar, the rising movements being utilized for lifting the operating pawl out of action, and the falling movements allowing the operating pawl to

55

60

65

70

75

be engaged with the rack, substantially as described.

11. In mechanism as claimed in claim 1, the combination of a fixed horizontal guide, the inclined guide being slidable on the horizontal guide, a rack mounted on the inclined guide, a locking pawl engaging the rack, a bar for rocking the pawl into and out of action, a lever for actuating the bar in the direction for disengag-

ing the pawl from the rack, a spring for moving the bar in the opposite direction, a spring controlled catch for securing the bar with the pawl out of action, means co-ordinated with the movements of the inclined slide for actuating the said lever, and a tappet on the slide for releasing the catch when the slide is returned to its initial position, substantially as described.

HARRY ALBERT GRIFFITHS.
